Primary Examiner — Mojtaba Tehrani(74) *Attorney, Agent, or Firm* — Kunzler Bean & Adamson, PC; Bryan Pitt(57) **CLAIM**

The ornamental design for a water gun, as shown and described.

DESCRIPTION

FIG. 1 is a top, front, right side perspective view of a water gun showing my new design;

FIG. 2 is a bottom, rear, left side perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is an enlarged view of the portion labeled “9” in FIG. 1; and,

FIG. 10 is an enlarged view of the portion labeled “10” in FIG. 1.

The dash broken lines show the features of the water gun that form no part of the claimed design. The dot-dash broken line rectangle frames define the boundary of an enlarged view and form no part of the claimed design.

1 Claim, 10 Drawing Sheets(56)
